UNITED STATES PATENT OFFICE

FRED J. McNAMARA, OF STOCKBRIDGE, MICHIGAN

SELF-SERVING ATTACHMENT FOR LIQUID VENDING PUMPS

Application filed July 23, 1930. Serial No. 470,095.

This invention relates to certain new and useful improvements in self-serving coin controlled mechanisms designed for attachment upon and for operating the plungers of liquid dispensing pumps.

One of the principal objects of the invention contemplates the provision and arrangement of coin introducing and conveying passages having means located in the path thereof to prevent operation of the pump by spurious coins.

An additional object of the invention consists of a coin operated clutch mechanism designed to establish operative connection between an exterior crank handle and the internal plunger or pump rod.

A further object of the invention embodies a coin removing element located in the path of movement of the clutch to release the coin subsequent to locking engagement of the clutch elements.

More specifically stated the device is provided with releasing elements located at intervals and for engagement with one of the clutch elements to release the pump plunger when reaching a predetermined position pursuant to the denomination of the coin.

With the above and other objects in view, the invention further consists of the following novel features and details of construction, to be hereinafter more fully described, illustrated in the accompanying drawings and pointed out in the appended claims.

In the drawings:—

Figure 1 is a front elevation of the present invention.

Figure 2 is a sectional view taken on line 2—2 of Figure 1.

Figure 3 is a top plan view of the invention partly broken away to illustrate the particular disposition and relative arrangement of a coin introducing slot and coin conveying means.

Figure 4 is a rear elevation of the present invention.

Figure 5 is a side elevation of the clutch elements.

Figure 6 is a top plan view of the arrangement disclosed in Figure 5.

Figure 7 is an enlarged fragmentary front

elevation of the coin introducing slot showing the discharge passage for spurious coins.

Referring to the drawings in detail wherein like characters of reference denote corresponding parts, the reference character 10 indicates generally a housing provided with an attaching flange 11 projecting outwardly in continuous formation about the entire perimeter thereof and to lie flush against the adjacent side of a conventional form of liquid dispensing pump, not shown, generally employed for gasoline and oil. A shaft member 12, carried by and forming a part of the present invention, carries a spur gear, not shown, for meshing engagement with the rack bar portion of the gasoline pump plunger rod in a manner to be better understood in the following description of the invention.

A stub shaft 13, having an enlarged socket portion 14 upon one end thereof and journaled within the bore of a box 15, carried by the housing 10, is designed to accommodate the outermost projecting end of the shaft 12 whereby the support for the latter is complete.

A worm shaft 16, journaled at intervals upon and between bearing members 17 and 18, has a worm portion 19 meshingly engaged with a worm gear 20 keyed or otherwise fixed to the outermost projecting end of the stub shaft 13. A crank handle, such as indicated at 21, for operating the worm shaft 16, is preferably provided with a ratchet connection therebetween whereby the shaft 16 may be operated only in a clockwise direction. Under ordinary circumstances, the shafts 12 and 13 are free and the gasoline or oil pump plunger rod will be normally retracted to occupy a lowered or inactive position.

A collar member 22, fixed upon the shaft 12, through the instrumentality of a cross pin 23, carries a clutch element 24 of disk like formation having radially disposed fingers or stops 25 upon one side thereof.

A disk member 26, carried by and operable in conjunction with an enlarged shoulder portion 27 formed upon the inner portion of the socket portion 14, carries a bearing face 28 upon its inner side for abutting engagement

with a corresponding portion 29 carried by the disk like clutch element 24 whereby the two clutch elements will be held and operated in positions spaced apart. Attaching or supporting ears 30 arranged upon the disk 26, provide the outer journals of rock shafts 31, each of which carry locking dogs and coin engaging elements 32 and 33 respectively operable through slots 34 and 35 in the disk 26. 10 Keys 36 are employed for the purpose of securing the locking dogs and coin engaging elements in position for use upon the rock shafts.

The disk like clutch element 24 is to be arranged upon the shaft 12 in such manner and position so that the coin receiving slots 37 inwardly projecting from diametrically opposite sides thereof, for the accommodation of coins of different denominations, may be 15 aligned or otherwise registered with the inwardly and laterally projecting portions of coin introducing slots 38 in the housing 10. Said slots are of L-shape formation and have their outermost ends in communication with 20 cylindrical openings 39 by means of which projecting of the operator's finger will be permitted to introduce the coin against the tension of a coin shifting or placing lever 40. The axis 41 for the lever 40 has a compression 25 spring 42 wound thereabout and engageable with one side edge of the lever 40 to normally dispose the latter to occupy the position shown in Figure 3 of the drawings whereby authorized coins of proper denomination 30 will be shifted inwardly through the laterally projecting portions of the passageways for accommodation within the slots 37. Coin holding fingers 43 carried by the collar member 22, are curved, adjacent their outermost ends, in conformity to the particular size 35 of the immediate coin and provided with seats 44 to hold the coins when the lever or crank 21 is being actuated to shift or otherwise rotate the disk 26 whereby the shoulder 45 of the intermediate coin engaging element 33 will engage and bear against the immediate coin with sufficient force to rock the immediate shaft 31, dislodge the spring pressed ball 46 holding the adjacent locking dog in normally inoperative position whereby the latter 45 will engage the adjacent of the clutch fingers 25 upon the disk 24 to lock the entire assemblage whereby the pump plunger rod may be actuated to dispense the amount of gasoline 50 or oil actually purchased.

Provision is also made for releasing the locking dogs 32 from the clutch fingers 25 at predetermined intervals whereby the pump piston or plunger will be disengaged after 60 the quantity of gasoline or oil has been dispensed. The aforementioned is accomplished through the provision and arrangement of projections 47 upon the shorter ends of the eccentrically mounted locking dogs 32 and 65 which are shifted for abutting engagement

with the inclined faces 48 of members 49 permanently located upon appropriate portions of the housing 10 and at intervals.

During the synchronous rotary motion of the lockingly engaged clutch elements, the 70 coin is shifted into position for contacting engagement with a coin releasing finger 50 which will allow the coin to drop down into the bottom or coin compartment of the housing. Each of the locking dogs 32 is provided with multiple pockets for the accommodation of the spring pressed balls 46 whereby the locking dogs will be yieldingly maintained against displacement from either 75 of their respective positions.

A leaf spring 51 is located adjacent the entrance of the coin receiving slots to deflect counterfeit light weight slugs or cardboard disks and magnets 52 are arranged immediately adjacent the coin receiving slots 37 in 80 the clutch element 24 to magnetize or otherwise attract spurious magnetically attractive coin substitutes whereby the attachment will be rendered fool-proof.

As will be noted from the foregoing description and accompanying drawings, the invention may be easily and effectively employed upon the usual crank shafts of liquid dispensing pumps of different makes and will permit the owners of gasoline filling stations and the like to leave their stations unattended along highways and other places.

The invention is susceptible of various changes in its form, proportions and minor details of construction and the right is here- 95 in reserved to make such changes as properly fall within the scope of the appended claims.

Having described the invention, what is claimed is:

1. A coin control comprising a housing, 105 aligned shafts journaled for rotation, clutch members mounted upon the respective shafts, one clutch member having a slot for receiving the coin, a dog pivoted upon the other clutch member and adapted to be swung by 110 the coin whereby the clutch members are locked, means for turning one of the shafts and means for ejecting the coin to release the dog and unlock the clutch members.

2. A coin control comprising rotatable 115 shafts arranged in axial alignment, clutch members mounted upon the respective shafts, one of the clutch members being provided with a coin receiving slot, a dog pivoted upon the other clutch member, an abutment carried on the first clutch member for engagement by said dog, a coin engaging element connected in common with the dog to shift the latter into obstructing relation with said abutment, means for turning one of the 120 shafts, and means for ejecting the coin after a specified angular movement of the shafts to release the dog and thereby unlock the clutch members.

3. A coin control comprising rotatable 125

shafts arranged in axial alignment, clutch members mounted upon the respective shafts, one of the clutch members being provided with a coin receiving slot, a dog pivoted upon 5 the other clutch member, an abutment carried on the first clutch member for engagement by said dog, a coin engaging element connected in common with the dog to shift the latter into obstructing relation with said abutment, 10 means for turning one of the shafts, and means for ejecting the coin after a specified angular movement of the shafts to release the dog and thereby unlock the clutch members, the dog and coin engaging element being 15 mounted on a common rock shaft.

4. A coin control comprising rotatable shafts arranged in axial alignment, clutch members mounted upon the respective shafts, one of the clutch members being provided 20 with a coin receiving slot, a dog pivoted upon the other clutch member, an abutment carried on the first clutch member for engagement by said dog, a coin engaging element connected in common with the dog to shift 25 the latter into obstructing relation with said abutment, means for turning one of the shafts, and means for ejecting the coin after a specified angular movement of the shafts to release the dog and thereby unlock the 30 clutch members, the dog and coin engaging element being mounted on a common rock shaft, and a spring pressed member engaging the dog to releasably retain it in its operative position of engagement with the abut- 35 ment.

5. A coin control comprising rotatable shafts arranged in axial alignment, clutch members mounted upon the respective shafts, one of the clutch members being provided 40 with a coin receiving slot, a dog pivoted upon the other clutch member, an abutment carried on the first clutch member for engagement by said dog, a coin engaging element connected in common with the dog to shift 45 the latter into obstructing relation with said abutment, means for turning one of the shafts, and means for ejecting the coin after a specified angular movement of the shafts to release the dog and thereby unlock the 50 clutch members, the dog and coin engaging element being mounted on a common rock shaft, the coin ejecting means comprising a fixedly mounted finger effecting a camming action on the coin to disengage it from the 55 coin engaging element.

In testimony whereof I affix my signature.
FRED J. McNAMARA.
